UNITED STATES PATENT OFFICE.

CHARLES H. AYARS, OF SALEM, NEW JERSEY, ASSIGNOR TO AYARS MACHINE COMPANY, OF SALEM, NEW JERSEY, A CORPORATION OF NEW JERSEY.

CAN-FILLING MACHINE.

Application filed February 12, 1927. Serial No. 167,657.

My invention relates to canning machinery and more particularly to a machine adapted to can whole fruits and vegetables.

It has been found very difficult to measure 5 fruits and vegetables, which are to be canned whole, without either crushing the fruit or cutting pieces from them with the leveling devices.

The principal object of my invention is to 10 provide means for feeding whole fruits and vegetables into the cans in measured quantities and the machine is particularly adapted to the canning of whole tomatoes on account of the care with which this tender fruit must 15 be handled.

Another object of my invention is to provide a machine having a large capacity and so compactly built that it requires but little 20 floor space.

Still another object of my invention is to 25 provide a machine of this character having means for readily changing the capacity of the measuring units.

These objects, and other advantageous ends 30 which will be described hereinafter, I attain in the following manner, reference being had to the accompanying drawings in which

Figure 1 is a perspective view of a canning 35 machine on which my invention has been installed,

Figure 2 a top plan view, partly in section and taken substantially on line 2—2 on Figure 3,

Figure 3 is a central sectional view taken 40 on the radial lines 3—3 on Figure 2,

Figure 4 is a sectional view, showing how the agitating plates overlap one another, taken on the line 4—4 on Figure 2, and

Figure 5 a top view, partly in section, taken 45 on the line 5—5 on Figure 3, some of the parts being broken away.

Referring now in detail to the drawings, the machine has a main frame 6 on which is 50 formed an auxiliary frame 7 supporting a bed plate 8 which is substantially circular in outline and disposed at an angle to the horizontal, as clearly shown in Figure 1. A shaft 9 is suitably journaled in frame 7 and bed plate 8. A hub 10 is slidably mounted on the upper end of shaft 9 and has arms 11 formed integral therewith which terminate in a circular conveyor plate 12 provided with a series of oval openings 13 from which slots 55 14 extend radially inward and slots 15 extend

radially outward. An agitating plate 16 is disposed over each opening 13 and is provided with a downwardly extending circular flange 17, which forms the upper half of a measuring cup, a stud 18 extending downwardly through slot 14, and a stud 19, extending downwardly through slot 15, which is provided at its lower end with a roller 20. Circular flanged cups 21 rest on bed plate 8 and telescope with flanges 17, thus forming adjustable measuring units.

The upper end of shaft 9 is bored and threaded to receive a screw shaft 22 which is revolvably mounted in hub 10 and held against axial movement by a collar 23 and a hand wheel 24, disposed below and above the top wall of hub 10. By rotating hand wheel 24 in one direction, plate 12 will be raised and the capacity of the measuring units increased while, if turned in the opposite direction, plate 12 will be lowered and the capacity of the measuring units decreased.

A cam track 25 is disposed near the outer edge of bed plate 8 and has its cam faces formed on the sides of a groove 25^a into which roller 20 depends. Cam track 25 extends from the lowest point on bed plate 8 to a little more than halfway to the highest point.

A sleeve 26 is mounted on and supported by hub 10, which is rotatable therein, and is provided with arms 27 which support a hopper base 28 disposed above agitating plates 16. A hopper 29 is secured in the hopper base and has a discharge opening slightly wider than the length of openings 13. The hopper has an upwardly inclined and open-ended extension 29^a, disposed above the path of travel of the filled cups, and the hopper plate has an upwardly extending curvilinear flange 28^a which extends around the path of travel of the filled measuring cups from the lowest to the uppermost, extends above the tops of the cups, embraces the end walls of the hopper extension, and serves to guide any fruit, which may roll from the tops of the cups, into the open end of the hopper extension, the inclination of the conveyor plate being sufficient to cause the surplus fruit to roll downwardly.

Assuming that whole tomatoes are to be 105 canned, they are placed in hopper 29 and plate 12 is rotated by means of power supplied to shaft 9. As the measuring units come beneath the hopper, they will be filled with tomatoes and carried around base plate 8 in 110

an anti-clockwise direction. Plates 16 will be held against circumferential or axial movement by studs 18 and 19 in slots 14 and 15 but will be reciprocated radially by rollers 20 en-

5 gaging the cam faces in groove 25^a, thus shaking the surplus tomatoes from the tops of the measuring units and allowing them to roll back into the hopper.

As each roller 20 leaves cam track groove 10 25^a, it is engaged by a rod 30 which prevents plate 16 from moving inwardly due to the force of gravity. A discharge opening 31 is formed in bed plate 8 at its highest point, communicating with a chute 32 which directs the 15 tomatoes into the can filling funnels and rod 30 is so positioned that the measuring units are led directly over this opening so that they may discharge their contents therethrough. Rod 30 terminates at a point just beyond 20 opening 31, thus releasing roller 20 and allowing plates 16 to move inwardly by the force of gravity.

A bracket 33 is secured to the underside of bed plate 8 at its lowest point and carries a 25 vertical post 34 which is threaded through a hand wheel 35. An arm 36 is provided at one end with a suitable aperture so that this end may rest on hand wheel 35 while its other end is rigidly secured to, and supports, hopper 30 per 29. This arrangement of parts is provided in order to prevent hopper 29 from rotating and from bearing directly on plates 16. It is also necessary to raise hopper 29 when plate 12 is raised to increase the capacity 35 of the measuring cups.

As handling tomatoes in this manner will cause them to discharge a considerable amount of juice, a juice hopper 37 is secured to a flange 38, formed on bed plate 8, and extends 40 substantially halfway around bed plate 8. It is considerably wider at its lowest point than at its upper ends so that its upper edge lies approximately in a horizontal plane. In order that the tomatoes, shaken from the 45 measuring units, by the cam track, will not be abraded by sharp corners and in order that juices will be directed downwardly over the top of plates 16, the lower edge of each plate is offset so that it overlaps the adjacent edge 50 of the adjoining plate, as plainly shown in Figure 4.

Each can, as it enters the machine from a can-feeding attachment 39, is supplied with a measured quantity of juice from a measuring 55 valve 40 which is supplied from hopper 37 by a centrifugal pump 41. The can then moves forwardly under a funnel 42, disposed directly beneath chute 32 and receives a measure of tomatoes. As this part of the machine 60 is not included in this invention and, as its parts and functions are known in the art, it will not be further described.

I find that a machine, made as above described, will measure and can a much larger 65 quantity of tomatoes than any other machine

of the same size, that the tomatoes are not bruised or cut, that the cans are evenly filled, and that the machine is easily kept in a sanitary condition.

While I have described my invention as taking a particular form, it will be understood that certain modifications may be made without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. In a can filling machine, an inclined bed plate having a discharge opening, a conveyor movable above the bed plate, a series of measuring units carried by the conveyor and slideable on the bed plate, a feed hopper disposed above the conveyor, means for reciprocating the measuring units, and means to actuate the conveyor whereby material may be carried by the measuring units from the hopper to the discharge opening.

2. In a can filling machine, an inclined bed plate having a discharge opening, a conveyor movable above the bed plate, a series of measuring units carried by the conveyor and slideable on the bed plate, a feed hopper disposed above the conveyor, means to agitate the measuring units, means to actuate the conveyor whereby material may be carried by the measuring units from the hopper to the discharge opening, and a plate having an upwardly extending flange extending from the hopper around the measuring unit registering with the discharge opening.

3. In a can filling machine, an inclined bed plate, a conveyor plate rotatable above the bed plate, a series of measuring units carried by the conveyor plate, a feed hopper disposed above the conveyor plate, means for reciprocating the measuring cups, and means to rotate the conveyor plate.

4. In a can filling machine, an inclined bed plate having a discharge opening, a series of measuring cups slideable on the bed plate, a conveyor plate rotatable above the bed plate, a series of agitating plates slideable on the conveyor plate, measuring cups formed on the agitating plates and telescoping with the cups on the bed plate, a hopper above the agitating plates, means to rotate the conveyor plate whereby the measuring cups may carry material from the hopper to the discharge opening, and means to reciprocate the agitating plates.

5. In a can filling machine; an inclined bed plate having a discharge opening; a series of measuring cups slideable on the bed plate; a power driven shaft mounted through the bed plate; a hub slidably keyed to the shaft; a conveyor plate secured to the hub; a series

of agitating plates slidable on the conveyor plate; measuring cups formed on the agitating plates and telescoping with the cups on the bed plate; a hopper above the agitating plates; a hopper base, mounted on the hub, carrying the hopper and extending around the measuring cup aligning with the discharge opening; and means to reciprocate the agitating plates.

10 6. In a can filling machine; an inclined bed plate having a discharge opening; a series of measuring cups slidable on the bed plate; a conveyor plate, having openings therein and slots extending inward and outward from 15 said openings, rotatable above the bed plate; a series of agitating plates slidable on the conveyor plate; measuring cups, formed on the agitating plates, extending through said openings and telescoping with the cups on 20 the bed plate; studs secured to the agitating plates and slidable in said slots; a hopper above the agitating plates; means to rotate the conveyor plate whereby the measuring cups may carry material from the hopper to 25 the discharge opening, and means to reciprocate the agitating plates.

7. In a can filling machine, an inclined bed plate having a discharge opening, a conveyor movable above the bed plate, a series 30 of agitating plates slidable on the conveyor, a cam track on the bed plate, a stud on each agitating plate adapted to engage the cam faces on the cam track, measuring cups carried by the agitating plates, a hopper disposed 35 above the agitating plates, and means to actuate the conveyor whereby the measuring cups may carry material from the hopper to the discharge opening and be agitated en route.

40 8. In a can filling machine, an inclined bed plate having a discharge opening, a conveyor movable above the bed plate, a series of agitating plates slidable on the conveyor, a cam track on the bed plate, a guide extending 45 from the cam track to the discharge opening, a stud on each agitating plate adapted to engage the cam faces on the cam track, measuring cups carried by the agitating plates, a hopper disposed above the agitating plates, 50 and means to actuate the conveyor whereby the measuring cups may carry material from the hopper to the discharge opening and be agitated en route.

9. In a can filling machine, an inclined bed plate having a discharge opening, a series 55 of measuring cups slidable on the bed plate, a conveyor movable above the bed plate, a series of agitating plates slidable on the conveyor, a cam track on the bed plate, a stud on each

agitating plate adapted to engage the cam 60 faces on the cam track, measuring cups carried by the agitating plates and telescoping with the cups on the bed plate, a hopper disposed above the agitating plates, means to raise and lower the conveyor and hopper, and 65 means to actuate the conveyor whereby the measuring cups may carry material from the hopper to the discharge opening and be agitated en route.

10. In a can filling machine; an inclined 70 bed plate having a discharge opening; a series of measuring cups slidable on the bed plate; a power driven shaft mounted through the bed plate; a hub slidably keyed to the shaft; a conveyor plate secured to the 75 hub; a series of agitating plates slidable on the conveyor plate; measuring cups formed on the agitating plates and telescoping with the cups on the bed plate; a hopper above the agitating plates; a hopper base, mounted 80 on the hub, carrying the hopper and extending around the measuring cup aligning with the discharge opening; a cam track on the bed plate; and a roller mounted on each agitating 85 plate and engaging the faces on the cam track.

11. In a can filling machine, an inclined bed plate having a discharge opening, an inclined conveyor plate rotatable above the bed plate, a series of measuring cups carried by 90 the conveyor plate, a feed hopper disposed above the conveyor plate, means to rotate the conveyor plate whereby the measuring units may carry material from the feed hopper to the discharge opening, and means for guiding 95 surplus material, which may fall from the filled cups, back into the hopper.

12. In a can filling machine, an inclined bed plate having a discharge opening, a series of measuring cups slidable on the bed plate, an inclined conveyor plate rotatable above the bed plate, a series of measuring cups carried by the conveyor plate and telescoping with the cups on the bed plate, a feed 100 hopper disposed above the conveyor plate and having an upwardly inclined extension with an open end, means to rotate the conveyor plate whereby the measuring units may carry material from the feed hopper to the discharge opening, and a flange, carried by 105 the hopper plate, extending around the path of travel of the filled cups and above the tops of the cups and embracing the end walls of the hopper extension.

In testimony whereof I have signed my 110 name to this specification.

CHARLES H. AYARS.
